COMBINED DOOR CLOSER AND DEODORIZER

Mike Guryn, Oak Lawn, Ill.

Application February 24, 1959, Serial No. 54,713

Term of patent 14 years

(Cl. D10—7)

Fig. 1 is a front elevational view of a combined door closer and deodorizer embodying my new design; and
Fig. 2 is a top plan view of the same.

I claim:

The ornamental design for a combined door closer and deodorizer, substantially as shown.
